UNITED STATES PATENT OFFICE.

SAMUEL G. RICHTER, OF DOLTONS STATION, ILLINOIS.

TURN-TABLE LOCK AND DERAILER CONTROL.

1,263,600.

Specification of Letters Patent. Patented Apr. 23, 1918.

Application filed February 23, 1918. Serial No. 218,640.

To all whom it may concern:

Be it known that I, SAMUEL G. RICHTER, a citizen of the United States, residing at Doltons Station, in the county of Cook and State of Illinois, have invented new and useful Improvements in Turn-Table Locks and Derailer Controls, of which the following is a full, clear, and exact description.

My invention relates to safety devices for railroad tracks, and particularly for preventing the wrecking of engines, locomotives and railway cars in turntable pits and at swinging bridges.

The object of my invention is to derail a locomotive or a car before it can reach the pit of an open turntable or the stream or depression crossed by a bridge, at such a distance therefrom that the wrecking of the same will be avoided, and it is also an object of my invention to do this by comparatively simple means which will set the derailer on the ball of the track at the same time the bolt or locking device of said turntable or bridge is manipulated to permit the latter to be moved and unset it when the turntable or bridge is locked. These and other objects are accomplished by the means hereinafter fully described, and as particularly set forth in the claims.

30 In the drawings:

Figure 1 is a plan view of broken away portions of the track approach and the end of a turntable showing my improvements applied thereto.

35 Fig. 2 is a longitudinal view of the same taken on dotted line 2—2, Fig. 1.

Fig. 3 is a longitudinal section taken on dotted line 3—3, Fig. 1, drawn to a larger scale.

40 Fig. 4 is a horizontal section taken on dotted line 4—4, Fig. 3.

Fig. 5 is a transverse vertical section taken on dotted line 5—5, Fig. 1, drawn to the same scale as Fig. 3.

45 Fig. 6 shows a transverse section of one of the rails of the approaching track looking toward the derailer, which latter is shown in dotted lines, while its seat is shown in solid lines.

50 Referring to the drawings, A represents a circular turntable pit; B a turntable having ties b, b, connecting the parallel beams of the frame thereof; C, C, the rails mounted

on said ties and D, D, the rails of the track approaching said pit. 55

My improvements comprise, broadly speaking, a longitudinally reciprocable bolt 8, which is mounted on the turntable between and parallel to rails C, C; a tubular casing 9 arranged longitudinally between tracks D, 60 D, into which said bolt is adapted to be shot; a derailer 10 located fifty to seventy-five feet away from pit A, and mechanism that utilizes the thrust of the bolt when it is shot into said tubular casing 9 to move the 65 derailer off of the track so as to leave an open track when the turntable is locked to bring rails C, C, and D, D, in alignment preparatory to running a locomotive or car onto said turntable, and to reset said derailer on 70 the track when the bolt is withdrawn from said casing and the turntable is moved so as to carry rails C, C, out of alignment with rails D, D, of said approaching track.

As shown in the drawings, bolt 8 is a 75 comparatively long metal bar that is mounted upon the ties parallel to rails C and reciprocated through the medium of a link 12 connecting it to an arm 13, which latter projects upwardly from a rock-shaft 80 14 journaled in suitable hangers 15 secured to and depending down from the longitudinal beams or equivalent structure of the frame of the turntable, substantially as shown in Fig. 2 of the drawings. Bolt 8 is 85 placed between and its reciprocable movement is guided by means of guide-plates 16, 16, and 17, 17; guide-plates 16 having flanges that overlap the longitudinal edges of the bolt and guide-plates 17 having 90 flanges upon which said bolt rests. This arrangement of the overlapping and underlapping flanges of guide-plates 16 and 17 is provided for the purpose of permitting of a certain limited vertical play of the end 95 of bolt 8 nearest the end of the turntable, where the bolt has securely mounted thereon a longitudinally disposed plate 18, the advanced end of which extends beyond the adjacent end of the bolt and is formed into a 100 hook 19, the extremity of which points downward and terminates in a horizontal plane a suitable distance above the horizontal plane of the top of the bolt. If desired, this hook may be strengthened by the 105 employment of ribs arising from its longi-

tudinal edges and the corresponding edges of plate 18, substantially as shown.

Tubular casing 9 is, preferably, rectangular in cross-section, and its base-plate or bottom 20 extends beyond the end thereof into which the hooked end of the bolt is adapted to enter, and when the casing is arranged in proper position the end of this extension terminates at the edge of the pit, substantially 10 as shown in Fig. 3, and is, preferably, slightly beveled. The adjacent end of the bolt is provided with a slightly undercut bevel so that when said bolt is shot toward the adjacent open end or mouth of casing 9 15 it will be slightly raised.

The inner surfaces of the vertical walls and the roof of the casing are beveled at its mouth, and the upper portion of said vertical walls are made thicker and provided 20 with longitudinal runways 22 that extend from its rear end to very near its mouth. Near said mouth these runways are inclined downward and terminate in and communicate with the longitudinal grooves in the 25 said vertical walls next the floor of the casing that result from and are incidental to making the upper portions of said walls thicker. These runways may be made in any other way, but, considering the rough usage 30 to which the casing is subjected, I prefer to make them as hereinbefore described.

Arranged and movable longitudinal within casing 9 is a dog 23 consisting of a suitably shaped metal bar of a length substantially corresponding to that of the bore of 35 the casing. The end of this dog nearest the bolt is provided with a transverse ridge 24 projecting upward therefrom, the ends of which are extended to provide lugs 25, 25. 40 The under sides of these lugs are in a horizontal plane corresponding to the lower edge of the thickened upper portion of the vertical walls of the casing, and the rear portions of these bottom edges are beveled, as shown 45 at 26, Fig. 3 of the drawings. The rear end of dog 23 is connected by a longitudinally extending rod or pipe line 27 of about fifty to seventy-five feet in length to the longer arm of a bell-crank 28, which latter is ful- 50 crumed at its angle to a suitable pivotal stud 29 secured to and arising from a plate secured to one end of the ties of the track, and the shorter arm of this bell-crank is pivotally connected to the adjacent end of a 55 transversely extending link 30 whose opposite end is connected to a lug projecting down from the derail block 31, the opposite end of which latter is suitably shaped to de- 60 raiil a locomotive or car when it is moved transversely onto the tread of rail D when said link is reciprocated toward said rail and adapted to be withdrawn away from said rail and unseated when said link moves longitudinally in the opposite direction.

65 This block may be made as disclosed in

Letters Patent of the United States, granted to S. W. Hayes, for derail Oct. 31, 1911, No. 1,007,102 and June 6, 1916, No. 1,185,663 and as shown in outline in Fig. 6 of the drawings, but it will be understood that any other derailing block or device which can be moved laterally to set on the tread of the rail to derail a locomotive or car passing over it will answer the purpose of my invention just as well as said block 31, and I, therefore, do not wish to be confined to the use of the same.

Casing 9 is retained in the position shown in the drawings in alinement with bolt 8 by means of triangular shaped guide-plates 32, 32, between which the end of the casing nearest the bolt is placed, and in order to permit of a limited vertical play of said casing I have provided the vertical retaining walls 33 of said plates with vertically elongated guide-openings 34 into which guide-lugs 35, 35, projecting laterally from said casing, enter and have a limited vertical play.

In order to operate my invention, rock- 90 shaft 14 is moved through the medium of a lever 36 secured to and projecting from one end thereof in one direction and imparts a movement to said shaft and to arm 13, which, through the medium of link 12, 95 shoots bolt 8 toward casing 9 so that the hooked end 19 thereof will enter the adjacent mouth of the same. When said bolt has been shot forward a sufficient distance 100 the end of the same below the horizontal plane of the extremity of hook 19 will come in contact with the adjacent end of dog 23 and as it continues to move in the same direction it moves the dog rearwardly, and lugs 25 at the ends of ridge 24 thereof enter 105 the adjacent ends of runways 22 and raise the adjacent end of said dog so that said ridge enters within the embrace of hook 19 and interlocks therewith. Dog 23 as it is thus moved to the rear moves pipe line 27 110 longitudinally and imparts motion to bell-crank 28, which latter through the medium of link 30 moves the derailing block off of rail D of the approaching track. When the turntable is thus locked so that the ap- 115 proaching track is open and alines with the track on the turntable, the locomotive or car can be run onto the turntable, and when in proper position the latter can be unlocked and turned to bring it into alinement with some other track that approaches the turn- 120 table pit and the locomotive or car can be run onto the same.

In order to unlock the turntable, lever 36 125 is moved so as to rock shaft 14 in the opposite direction to that just described, and through the medium of arm 13 and link 12 withdraws bolt 8 from the casing. As the hooked end of this bolt is thus withdrawn it pulls dog 23 along with it until the ridged 130

end thereof is directed downward by the inclined forward portion of runways 22, whereupon it releases its hold upon the bolt, which latter continues its withdrawal movement until the contiguous end thereof passes and clears the junction between the end of the turntable and the edge of the pit. As dog 23 is pulled longitudinally forward toward the pit by the hooked end of the bolt, 5 as just stated, pipe line 27 moves bell-crank 28 so that it, through the medium of link 30 moves the derail block so that the derailed end thereof is reset on the ball of rail D. When the derail block is in this 10 set position, any locomotive or car attempting to pass over the same will be derailed and immediately stopped by the engineer, and thus prevented from pitching into the turntable pit and wrecked.

20. What I claim as new is:

1. The combination with a movable structure having a railroad track thereon, and a stationary approaching railroad track with which said movable track is adapted 25 to be alined, of coacting locking devices for retaining said tracks in alinement, one of which is mounted on said structure and the other on the stationary approach thereto, a derailier, and means operatively connected 30 to said last mentioned device for demounting said derailier from one of the rails when said devices are interlocked and mounting the same on said rail when said devices are unlocked.

35. 2. The combination with a movable structure having a railroad track thereon and a stationary approaching railroad track with which said movable track is adapted to be alined, of coacting locking devices for retaining said tracks in alinement, one of which is mounted on said structure and the other on the stationary approach thereto, a laterally movable derailier, and means operatively connected to said last mentioned 40 device for demounting said derailier from one of the rails when said devices are interlocked and mounting the same upon said rail when said devices are unlocked.

45. 3. The combination with a movable structure having a railroad track thereon, and a stationary approaching railroad track with which said movable track is adapted to be alined, of coacting reciprocable bolt and casing into which the same is shot for retaining said tracks in alinement, one of which is mounted on said structure and the other on the stationary approach thereto, a 50 derailier, and means operatively connected to said last mentioned bolt for demounting said derailier from one of the rails when said bolt and casing are interlocked and mounting the same upon said rail when said bolt and casing are unlocked.

55. 4. The combination with a movable structure having a railroad track thereon, and a

stationary approaching railroad track with which said movable track is adapted to be alined, of a longitudinal reciprocable bolt on the end of said structure, a longitudinally disposed casing on the stationary approach 70 thereto into which said bolt is adapted to be shot, a derailier, and means actuated by said bolt when within said casing to demount said derailier from one of the rails of the approaching track, and to mount said 75 derailier upon the track when it is withdrawn from said casing.

5. The combination with a movable structure having a railroad track thereon, and a stationary approaching railroad track with 80 which said movable track is adapted to be alined, of a longitudinal reciprocable bolt on the end of said structure, a longitudinally disposed casing on the stationary approach 85 thereto into which said bolt is adapted to be shot, a derailier, and means engaged and actuated by said bolt when within said casing to demount said derailier from one of the rails of the approaching track, and to mount said 90 derailier upon the track when it is withdrawn from said casing.

6. The combination with a movable structure having a railroad track thereon, and a stationary approaching railroad track with 95 which said movable track is adapted to be alined, of a longitudinal reciprocable bolt on the end of said structure, a longitudinally disposed casing on the stationary approach 100 thereto into which said bolt is adapted to be shot, a derailier, a device within said casing actuated by said bolt, and means to which said device imparts motion that demounts 105 said derailier from one of the rails of the approaching track, and mounts said derailier upon the track when it is withdrawn from said casing.

7. The combination with a movable structure having a railroad track thereon, and a stationary approaching railroad track with which said movable track is adapted to be 110 alined, of a longitudinal reciprocable bolt on the end of said structure, a longitudinally disposed casing on the stationary approach thereto into which said bolt is adapted to be shot, a derailier, a reciprocable device 115 within said casing actuated by said bolt, and means to which said device imparts motion that demounts said derailier from one of the rails of the approaching track, and mounts said 120 derailier upon the track when it is withdrawn from said casing.

8. The combination with a movable structure having a railroad track thereon, and a stationary approaching railroad track with which said movable track is adapted to be 125 alined, of a longitudinal reciprocable bolt on the end of said structure, a longitudinally disposed casing on the stationary approach thereto into which said bolt is adapted to be shot, a derailier, a reciprocable de- 130

vice which is pushed in one direction by said bolt when the latter is shot into said casing, and is dragged in the opposite direction when said bolt is withdrawn from the 5 casing, and means actuated by said device to demount said derailer from one of the rails of the approach track when said bolt is shot into the casing and mounts the derailer upon the track when the bolt is withdrawn 10 therefrom.

9. The combination with a movable structure having a railroad track thereon, and a stationary approaching railroad track with which said movable track is adapted 15 to be alined, of a longitudinal reciprocable bolt on the end of said structure, a longitudinally disposed casing on the stationary approach thereto into which said bolt is adapted to be shot, a derailer, a reciprocable 20 device with which said bolt interlocks when the latter is shot into said casing and pushed in one direction, and is dragged in the opposite direction and released thereby when said bolt is withdrawn from the casing, and 25 means actuated by said device to demount said derailer from one of the rails of the approach track when said bolt is shot into the casing and mounts the derailer upon the track when the bolt is withdrawn 30 therefrom.

10. The combination with a movable structure having a railroad track thereon and a stationary approaching railroad track with which said movable track is adapted to be 35 alined, a reciprocable bolt which is secured on said structure and has a hook on its advanced end, a longitudinally disposed tubular casing secured on the stationary approach to said structure, a longitudinally reciprocable 40 dog within the bore of said casing which is engaged by said hook when the bolt is shot into said casing and pushed in one direction and dragged in the opposite direction by said hook and returned to its 45 original position when the bolt is withdrawn from said casing, a derailer, and means actuated by said dog to demount said derailer from one of the rails of the approach track when the dog is pushed and mounts the 50 same when the dog is dragged.

11. The combination with a movable structure having a railroad track thereon and a stationary approaching railroad track with which said movable track is adapted to be 55 alined, a reciprocable bolt which is secured on said structure and has a hook on its advanced end, a longitudinally disposed tubular casing secured on the stationary approach to said structure, a longitudinally reciprocable 60 dog within the bore of said casing which is provided with a transverse ridge and which is engaged by said hook when the bolt is shot into said casing and pushed by the bolt in one direction and dragged in 65 the opposite direction by said hook and re-

turned to its original position when the bolt is withdrawn from said casing, a derailer, and means actuated by said dog to demount said derailer from one of the rails of the approach track when the dog is pushed and 70 mounts the same when the dog is dragged.

12. The combination with a movable structure having a railroad track thereon and a stationary approaching railroad track with which said movable track is adapted to be 75 alined, a reciprocable bolt which is secured on said structure and has a hook on its advanced end, a longitudinally disposed tubular casing secured on the stationary approach to said structure, a longitudinally reciprocable 80 dog within the bore of said casing which is provided with a transverse ridge, which as said bolt pushes said dog before it is raised and interlocks with said hook and remains in engagement therewith until returned to its original position, a derailer, and means actuated by said dog to mount said derailer upon one of the rails of the approaching track when said dog moves in 85 one direction and demount the same when the dog moves in the opposite direction.

13. The combination with a movable structure having a railroad track thereon, and a stationary approaching railroad track with which said movable track is adapted to be 95 alined, of a reciprocable bolt having a hook extending from its advanced end which is secured on said structure, a tubular casing mounted on the stationary approach which is rectangular in cross-section and has longitudinal runways in the vertical sides of its bore the ends of which nearest said bore are inclined downward, a longitudinally reciprocable dog having a transverse ridge on its end nearest said bolt that has lugs projecting from its ends that enter said runways, a derailer, and means connected to and actuated by said dog that mounts said derailer on one of the rails of the approach track when the dog is moved in one direction and demounts the same when the dog is moved in the opposite direction.

14. The combination with a movable structure having a railroad track thereon, and a stationary approaching railroad track with 115 which said movable track is adapted to be alined, of a reciprocable bolt having a hook extending from its advanced end which is secured on said structure, a tubular casing mounted on the stationary approach which 120 is rectangular in cross-section and has longitudinal runways in the vertical sides of its bore the ends of which nearest said bore are inclined downward, a longitudinally reciprocable dog having a transverse ridge on its end nearest said bolt that has lugs projecting from its ends that enter said runways, a transversely movable derailer, and means consisting of a longitudinally extending 125 rod, a bell-crank and a link and actuated 130

by said dog that mount said derailer on one of the rails of the approach track when the dog is moved in one direction and demount the same when the dog is moved in the opposite direction.

15. The combination with a movable structure having a railroad track thereon, and a stationary approaching railroad track with which said movable track is adapted to be alined, of coating locking devices for retaining said tracks in alinement, one of which is mounted on said structure and the other on the stationary approach thereto, an

obstacle for stopping the progress of the wheels of a railroad vehicle on one of the 15 rails of said approaching track, and means actuated by said movable structure that remove said obstacle from in front of said wheels.

In witness whereof I have hereunto set 20 my hand this 29th day of January 1918.

SAMUEL G. RICHTER.
